ATTORNEY.

UNITED STATES PATENT OFFICE.

WILLIAM ERNEST KERSHAW, OF PHILADELPHIA, AND CARROLL HODGE, OF RADNOR, PENNSYLVANIA.

BATTERY-CELL FILLER.

Application filed July 8, 1922. Serial No. 573,748.

To all whom it may concern:

Be it known that we, WILLIAM ERNEST KERSHAW, a citizen of the United States, residing at Philadelphia, in the county of Philadelphia and State of Pennsylvania, and CARROLL HODGE, a citizen of the United States, residing at Radnor, in the county of Delaware and State of Pennsylvania, have jointly invented a new and useful Improvement 10 in Battery-Cell Fillers, of which the following is a specification.

The principal object of the present invention is to provide a cell filler adapted for attachment to a hose or tube and in which the signal and its battery and circuit connections and all the other parts are portable as a unit at the end of the hose or tube through which the supply of fluid is delivered. Another object is to facilitate the 15 operation of filling inconveniently located cells. The third object of the invention is to provide for the use of a comparatively small battery which does not add appreciably to the weight of the device; and another 20 object of the invention is to provide a convenient, efficient and simple cell filler.

The invention will be claimed at the end hereof but will be first described in connection with the embodiment of it chosen from 25 other embodiments for the sake of illustration in the accompanying drawings forming part hereof and in which

Figure 1 is a side view showing some of the principal concealed parts in dotted lines.

Fig. 2 is a top or plan view of the right-hand end of the device shown in Fig. 1 with parts omitted, and

Fig. 3 is a sectional view illustrating diagrammatically circuit connections.

In the drawings 1, generally, is a handle or stock, as of wood, internally chambered as at 2 and forked or bifurcated at 3. 4 is a signal lamp arranged through the wall of the stock or handle and visible from the 40 outside thereof. As shown the lamp projects through a flat 5 provided on the stock. 6 is a battery arranged in the chamber 2 of the stock and it is removable through the end of the stock which is normally closed by a detachable cap 7 having a contact spring 8 and constituting one of the terminals of the battery. The contact 9 constitutes the other terminal of the battery. The nozzle 10 is movably mounted in the 45 bifurcation 3 and is provided with contacts

11 and 12 insulated from each other by insulation 13 and adapted to be bridged by liquid as will be hereinafter described. The contact 11 may well be of copper material and it is connected to the positive end of the 50 battery as by a conductor 14. The contact 12 may well be of leaden material and it is connected to the negative end of the battery as by a conductor 15. The contact 11 is shown as made in two parts of which the 55 part 11^a is detachable by means of a screw thread and this is advantageous because the part 11^a is subject to wear and can be easily removed for renewal, and when worn does not interfere with the operation of the device because the lead contact 12 controls the 60 level at which the circuit is closed and the signal given. 16 is a collar mounted on and insulated from the other parts of the nozzle and it serves as a limit stop when the nozzle 65 is inserted in the battery jar and it also serves to limit the range of movement of the nozzle in respect to the stock or nozzle. The contact 11 is hollow and is provided with a head 17 to which the handle or stock is 70 pivoted and with an angle bend which receives the end of the hose or tube 18 which passes through a hole in the end of a centrally pivoted spring pressed finger released 75 lever 19 shown as carried by a band 20 on the stock or handle. The end of the nozzle 80 11^a may be provided with spaced feet or projections 21 to insure a fluid outlet even when the end of the nozzle is in contact with a flat surface and with a screen 22 85 which prevents or opposes dripping and which is exposed to water.

In use the nozzle is inserted into the filling opening of a battery jar *a*, and the collar 16 fixes the depth of the insertion. For this 90 purpose the nozzle may be moved in respect to the stock or handle thus facilitating the operation. The lever 19 is pressed toward the stock or handle thus releasing the hose so that fluid runs through the hose and nozzle 95 and fills the battery *a*. When this happens the circuit is closed through the electrolyte and the lamp is lighted, indicating that the cell has been filled to the required level. Thereupon the handle 19 is released and the 100 filler can be conveniently used for filling other cells since it can be easily transported, because all of its parts, including the electric signal and its battery, are connected with and carried by it. A new battery can be pro- 105 110

vided by removing the cap 7. When the contacts are bridged by the electrolyte the oxygen given off at the copper contact 11 by electrolytic action combines with the copper 5 forming oxide of copper which is dissolved in the electrolyte. In this way the contacts oppose practically no counter electro-motive force to the voltage of the battery 6, so that the latter may be comparatively small. 10 Copper and leaden materials are examples of electrodes which oppose little or no counter electro-motive force under the conditions presented in the operation of the described filler. 15 It has been said that the part or tip 11^a of the conductor nozzle 11, is removable or detachable from the conductor nozzle 11, and for that purpose the conductor nozzle 11 terminates at a higher level, or is shorter than 20 the conducting contact 12 by which the normal level of the acid solution is limited, so that the joint or thread between the parts 11 and 11^a is exposed to water flowing through the parts 11 and 11^a and not to acid, and 25 therefore the joint or thread between the parts 11 and 11^a does not become corroded but can be easily detached.

We claim:

30 1. A portable cell filler comprising in combination a handle or stock internally chambered and bifurcated, a fluid supply tube arranged outside of said chambered portion of the stock, a signal lamp arranged through the wall of the stock and visible from the 35 outside thereof, a battery arranged in the chamber, a nozzle movably mounted in the bifurcation and provided with contacts adapted for liquid bridging, a controlling valve for the nozzle, and circuit connections for the battery, signal and contacts. 40

2. In a cell filler the combination of a 45 stock or handle, a battery and signal mounted on the stock, a nozzle movable in respect to the stock or handle and provided with contacts, a fluid supply for the nozzle including a valve carried by the stock, and circuit connections carried by the stock or handle, substantially as described.

3. In a cell filler the combination of a

handle or stock internally chambered and 50 carrying an electric signal, a battery mounted in the chamber and carried by the stock, a fluid supply for the nozzle arranged outside of the chambered portion of the stock, and circuit connections for the battery and 55 signal including contacts adapted for liquid bridging.

4. In portable cell fillers the combination of a battery mounted on the cell filler and contacts adapted for insertion in electrolyte and 60 of which one is of copper and is connected with the positive end of the battery and of which the other is of leaden material and is connected with the negative end of the battery, the leaden material and copper under 65 electrolytic action being substantially devoid of counter electro-motive force whereby a comparatively small battery suitable for application to the stock can be employed.

5. In a portable cell filler the combination 70 of a battery and contacts connected therewith and adapted for insertion in electrolyte and being respectively of copper and leaden materials which do not develop counter electro-motive force under electrolytic 75 action whereby the battery can be small and portable.

6. In a portable cell filler the combination of a sleeve of insulating material, a leaden contact tube arranged outside of the insulating sleeve, a tube of conducting material arranged inside of the insulating sleeve, and a contact of copper material projecting beyond the insulating sleeve and having detachable connection with the conducting 85 tube, substantially as described.

7. In a cell filler the combination of provisions including a contact by which the high level of the electrolyte is indicated, a conductor nozzle through which water is 90 supplied, and a joint in the conductor nozzle located above the high level of the electrolyte and in the path of the water and by which the tip of the conductor nozzle can be readily removed.

WILLIAM ERNEST KERSHAW.
CARROLL HODGE.
